UNITED STATES PATENT OFFICE

1,989,232

FULL FASHIONED KNITTING MACHINE

Kenneth Howie, Norristown, Pa., assignor to
Wildman Mfg. Co., Norristown, Pa., a corpora-
tion of Pennsylvania

Application June 3, 1933, Serial No. 674,242
Renewed December 5, 1934

9 Claims. (Cl. 66—129)

The invention is an improvement in the mechanism for making the high splice in full fashioned hosiery such as is disclosed in application for Letters Patent of the United States filed by Kenneth Howie and Charles C. Krieble Feb. 4, 1932, Ser. No. 590,942, Patent No. 1,982,991. One object of the present invention is to provide improved connections for operating the stops for determining the stroke of the yarn carrier means 10 in forming the reinforced area above the heel, so that free space of maximum area will be afforded between the centrally disposed stops and the selvage stops for the adjustment of the latter to a point in relatively close relation to the center 15 of the stop organization so that the English form of stocking readily can be made as well as the French form.

Other objects will appear from the following specification and the appended claims.

20 In the drawings

Figure 1 is a diagrammatic plan view of a portion of the knitting machine embodying a part of the invention.

Fig. 2 is a rear view of Fig. 1.

Fig. 3 is a side view looking from the left of Figs. 1 and 2.

Fig. 4 is a detail plan view of the stop mechanism.

Fig. 5 is a detail sectional view showing stop members in elevation on line 5—5 of Fig. 4.

Figs. 6 and 7 show details.

Fig. 8 is a detail view of part of pattern mechanism and connections leading therefrom for controlling a ratchet shield.

35 In these drawings 26 Fig. 1 indicates the endless flexible bands, the front stretches of which have the yarn guides mounted thereon to be moved along the straight needle row by driving means like those shown in said patent application, but not shown herein.

The stops for arresting the yarn carrier bands for determining the tapered reinforced or spliced area are shown at S. These stops project down into the path of dogs or projections on the bands 45 so that when the dogs strike the stops the yarn carrier band will be arrested to determine the margin of the reinforced area of fabric, it being understood that the driving device for the bands has frictional engagement therewith so that when 50 the band is arrested by the stop the friction drive means can pass on to the limit of its regular stroke. These stops project downwardly from the ends of bars s4 slidably mounted in the bracket 36x arranged at the center of the length of the 55 rear stretches of the flexible yarn carrier bands.

The slide bars s4 have rack bars s8 associated therewith, these being adjustable on the slide bars, so that the stops S can be accurately set in position. For this purpose the slide bars have upwardly extending terminal projections 1 5 through which screws 2 extend into the rack bars. At their other ends the rack bars are held to the slide bars by screws 3 extending through slots or notches 4 in the rack bar into the slide bar. Pinions s1 engage these racks. Rock shafts 10 s2 have the said pinions mounted thereon. The rock shafts are mounted in the fixed bracket 36x. At their rear ends these rock shafts have gears s5 arranged adjacent each other, though spaced sufficiently far apart to receive between them a 15 vertically movable rod q7 having rack teeth s7 on its opposite sides meshing with the gears s5 so that when this vertically arranged rack bar is moved vertically the gears s5 will be turned and the rock shafts will be operated so that the pinions s1 will be operated to move the racks s8 and slide bars s4 will be operated to adjust the stops S along the carrier bands so as to determine the lengths of movements of said bands and consequently the tapered form of the reinforced area or high splice. The same vertical movement of the rack bar q7 will result in the adjustment of 20 the two stops S in opposite directions, one moving to the right and the other to the left along their respective flexible band yarn guide carriers to 25 make the reinforced area above the heel tabs of the stocking blank. The vertically arranged rack bar is guided in the bracket q1. This rack bar is operated vertically step by step by a cam q with which engages a roller q8 at the lower end of the 30 rack carrying bar q7. The cam q is mounted for rotation in the bracket q1. It is operated by a ratchet wheel q3 and a pawl q2, said pawl being carried by a lever b3 operated by a cam bx. Engagement of the pawl with the ratchet is controlled by a shield q9 which in turn is controlled by a flexible rod q10 extending from suitable pattern mechanism through a guide tube q13. The shield is pivotally mounted at 6 to a bracket arm 7 and it is stressed by a spring 8 tending to move 45 the shield outwardly so as to present its edge 9, upon which the pawl rides out beyond the teeth of the ratchet.

The cam preferably has rests or steps on its periphery the distance from center to center of 50 which represents the length of the step movements imparted to the cam by the pawl and ratchet. A spring q14 stresses the rack bar q7 downwardly so as to keep the roller q8 upon the periphery of the cam q and return the stop car- 55

rying slides s_4 with stops S to their positions of rest.

There is a push block q_6 carrying the roller q_8 and secured to the lower end of the rack bar q_7 .

- 5 This push block operates a push rod p_4 through a guide tube p_5 like in the application referred to, to operate a lever at the front of the machine for adjusting said lever along a tapered cam so as to be operated by said cam for different periods, thus 10 to control the loop regulating rock shaft which controls the lengths of the loops all as in the application before referred to. The guide tube p_5 extends in a circuitous position to the front of the machine so as to guide the flexible rod p_4 to its point of work. Two actions therefore take 15 place when the rack bar q_7 together with the push block q_6 rise, one of these actions being the adjustment of the stops S for arresting the reinforcing yarn carriers at the prescribed varying 20 limits of their stroke to make the tapered reinforced areas of the stocking blank and the other action being the operation of the loop length regulating shaft to get longer loops for the reinforced areas.
- 25 It will be noted that the connections extending from the cam q (which conveniently, is located at the rear of the machine) to the stops S and including the vertically movable rack bar q_7 , the 30 pinions, rock shafts s_2 and slide bars s_4 provide an operating organization for the stops S which occupy none of the space laterally beyond the stops S or in other words these operating connections do not occupy any of the space between the stops S and the outside selvage stops carried 35 by the brackets $36e$ as in the application referred to. These brackets $36e$ which carry the outside selvage stops for arresting the yarn carriers to define the outside limits of the fabric are adjustable towards each other as the fabric is being knit 40 and fashioned by the screw shaft sections 43 operated by the gearing $43a$, $43b$, through connections described in said application, and the adjustment of these outside selvage stops defines the shape of the fabric. At H_1 are shown the home stops for 45 the yarn carrier bands, this being a feature of said application.

By reason, therefore, of the employment of the operating connections for the stops S of a character which will occupy only the space between 50 the vertical planes, extending transversely of the yarn carrier bands, in which said stops S lie, it will be understood that the outside selvage stop by the adjustment of their brackets $36e$, $36e$ inwardly towards each other can be brought close 55 to the transverse center line of the organization. The reason that this capacity to adjust the outside selvage stop inwardly towards each other to a maximum degree is of advantage, lies in the circumstance that in making an English form of 60 full fashioned stocking blank wherein the instep portion of the foot is knitted as an integral or continuous extension of the leg and heel tab blank, the foot portion of the blank is of less width than the foot of what is known as the French full 65 fashioned stockings. This difference between the English and French styles of blank requires that in making the English style the outside selvage stops must be capable of adjustment nearer to the transverse center of the machine than is possible with the organization disclosed in said 70 patent application wherein flexible push rods were employed for adjusting the stops S and which rods or wires, by reason of their location interfered with the same degree of inward adjustment 75

of the outside selvage stops as is possible with the present means of adjusting said stops S , S .

This rack and pinion arrangement, including the vertical rack q_7 , the rock shafts s_2 , the pinions and the racks s_8 takes up little room in a direction lengthwise of the yarn carrier bands, and no more than do the stops S , S , whatever the adjusted position of the latter may be. Hence, there is ample space for the adjustment inwardly towards the transverse center line of the machine of the outside selvage stops carried by the brackets $36e$.

10 The ratchet wheel q_3 has a low tooth at 5 by means of which the normal position of rest, or in other words, the starting point of the cam q is 15 determined. By this tooth also the cam will be brought into proper time with the other parts of the machine in the event that a press off takes place and a new fabric is started. In such a circumstance the operator will not have to pay any 20 attention to resetting the cam into properly timed relation with the progress of the work being performed, as the resetting of this cam will be taken care of automatically. This cam is operated during the making of the high splice or reinforced 25 area above the heel by the pawl q_2 engaging the teeth on the ratchet wheel q_3 .

For this action there is provided a pattern controlled flexible rod q_{10} to move the shield inwardly to expose the teeth of the ratchet to the 30 action of the pawl, but to bring the cam to the starting point the flexible rod will set the shield (which holds the pawl out of the ratchet) in a half way position so that while the high teeth will be engaged by the pawl the low tooth will 35 be shielded from the action of the pawl and hence the ratchet wheel will come to rest at the starting point. No matter, therefore, what angular position the cam and ratchet may be in if the shield is set in the half way position the pawl will keep 40 on moving the ratchet wheel and the cam until the low tooth comes around to stop the cam at its position of rest, so that it may be started up in proper timed relation with the other parts of the machine.

45 This action of automatically setting the cam q to its starting position, in case of a press off, will be carried on during the time that the yarn carrier bands, which carry the splicing yarns, are at rest, i. e. not engaged by the appropriate pawls 50 of the reciprocating driver described in said application.

As shown in Figs. 1, 2, 4 and 5, the stops S when in normal position for beginning the formation of the high splice lie close to the opposite 55 sides of the bracket $36x$. When they are operated by the racks and pinions they move in opposite directions away from the transverse center line of the organization and therefore away from the bracket. This movement is step by 60 step as will be clear from an inspection of the cam q . Referring to Figs. 1, 4 and 5, it will be seen that the stop S at the right of the bracket $36x$ and consequently to the right of a vertical plane passing through the center of the said bracket 65 transversely of the yarn carriers is carried by the slide bar, which together with its rack extends leftward from said right hand stop. On the contrary the left hand stop S which lies to the left of said bracket in the said Figures 1 and 70 4 is carried by a slide bar, which together with its rack extends across said bracket and terminates to the right thereof.

The pinions s_1 engage the inner ends of their respective racks as in Figs. 4 and 5, and when 75

these are turned by the upward movement of the centrally disposed rack bar q_7 acting through pinions s_5 and shafts s_2 the rack bars with their slide bars will be drawn inwardly towards the center of the organization thus clearing the space at opposite sides of the bracket while their stops S will be moved outwardly towards the outside selvage stops carried by the brackets $36e$.

It being one of the objects of the invention to make the brackets $36e$ carrying the selvage stops to be adjusted close to the transverse center line of the machine, the assembly devised to that end involves motion transmitting means between the cam q and the stops S which are arranged substantially at or adjacent to said center line, leaving the space between said stops S and the selvage stops carried by the brackets $36e$ free from obstructing elements. Therefore, the assembly, in the particular arrangement shown, as an example of my invention, includes the rack bar q_7 at the said center line and the closely adjacent pinions and rock shafts. The invention in this regard, however, is not limited to the specific means disclosed. One characteristic of the assembly may be mentioned in that the stops S are operated by rotary elements arranged near the transverse center line of the assembly which rotary elements, i. e. the pinions, are operated by a reciprocating member like the bar q_7 and said rotary elements transmit reciprocating movement to the stops S by way, for instance, of the slide bars, and racks, to which, however, the invention in its broader aspect is not limited.

In Fig. 8 is shown a pattern chain x having a high button x_1 and a low button x_2 . The high button will operate a lever y , which, in turn, will operate the flexible rod q_{10} to set the shield q_9 to allow pawl q_2 to advance the ratchet q_3 one tooth.

When no button is under the lever y , the shield q_9 covers the ratchet teeth and the pawl will not engage the ratchet.

When the reinforced area is completed, and the cam q is to be reset, or retimed, so as to occupy its starting position, a low button x_2 will operate lever y to push the flexible rod q_{10} only enough to operate shield q_9 to enable pawl 5 to engage the regular teeth on the ratchet, but not enough to expose the low tooth 5 so that when this low tooth comes around to the pawl, the ratchet will not be operated by the pawl, but will come to rest in its starting position. The cam q is then in proper position to start another reinforced area.

I claim:

1. In combination in a full fashioned knitting machine, reciprocating yarn guide carriers, adjustable outside selvage stops to arrest the carriers for fashioning, reinforcing yarn guide carrier stops disposed between the selvage stops and on opposite sides but adjacent a vertical plane passing transversely and midway of the length of the yarn guide carriers for limiting the stroke of said reinforcing yarn guide carriers, and means for adjusting the said centrally-disposed reinforcing yarn guide carrier stops comprising a cam and means operated thereby and disposed substantially in said transverse vertical plane midway the length of the yarn guide carriers, with connections from said means to said stops, the region between said reinforcing yarn guide carrier stops and the opposing selvage stops being free from obstruction to permit adjustment of said selvage

stops inwardly to position in close relation to each other, substantially as described.

2. In combination in a full fashioned knitting machine, reciprocating yarn guide carriers, adjustable outside selvage stops to arrest the carriers for fashioning, reinforcing yarn guide carrier stops disposed between the selvage stops and on opposite sides but adjacent a vertical plane passing transversely and midway of the length of the yarn guide carriers for limiting the stroke of said reinforcing yarn guide carriers, and means for adjusting the said centrally-disposed reinforcing yarn guide carrier stops comprising a cam, a rod operated vertically by said cam and connections from said rod to both of the reinforcing yarn guide carrier stops, said vertically movable rod being located in said transverse vertical plane passing centrally between said last mentioned stops.

3. In combination in a full fashioned knitting machine, adjustable stops for splicing yarn carriers to determine the limit of the reinforced areas, and means for adjusting said stops automatically, said means comprising slide bars carrying said stops, rack teeth associated with the slide bars, pinions meshing with the racks, shafts carrying the pinions, other pinions on said shafts, a vertically arranged rack bar engaging said last mentioned pinions, and means for moving the vertical rack bar up and down to simultaneously operate the pinions and the slide bars carrying the stops, said mechanism leaving room beside it for the adjustment towards each other of outside selvage stops, substantially as described.

4. In a full fashioned knitting machine, adjustable stops at substantially the center line of the machine for arresting reinforcing yarn guide carriers for defining the reinforced area of the fabric, and means for operating said stops comprising rotary means located substantially at said center line, a cam with a connection to said rotary means for operating the same, and a connection between the said rotary means and the stops, the connection leading from the cam to the rotary means comprising a rack bar operated by said cam and a pair of pinions operated by the rack bar, connected with the shafts of the rotary means, substantially as described.

5. A high splice mechanism for full fashioned knitting machines comprising stops for arresting the yarn guide carriers for reinforcing yarn, a cam with connections to said stops for adjusting them to define the reinforced area, a ratchet for operating the said cam having a low tooth, a pawl with means for operating the same to turn the ratchet and means for controlling the position of the pawl relative to the ratchet to take the high teeth and not the low tooth whereby the cam with the stops will be restored to starting position.

6. A high splice mechanism for full fashioned knitting machines comprising stops for arresting the yarn guide carriers for reinforcing yarn, a cam with connections to said stops for adjusting them to define the reinforced area, a ratchet for operating the said cam having a low tooth, a pawl with means for operating the same to turn the ratchet and means for controlling the position of the pawl relative to the ratchet, to miss all of the ratchet teeth for maintaining the cam in its position of rest, to take all of the teeth for making the cam perform a cycle of operation, and to take the high teeth but miss the low tooth whereby the cam will come to rest at its starting point, substantially as described.

7. A high splice mechanism for full fashioned knitting machines comprising stops for arresting the yarn guide carriers for reinforcing yarn, a cam with connections to said stops for adjusting them to define the reinforced area, a ratchet for operating the said cam having a low tooth, a pawl with means for operating the same to turn the ratchet and means for controlling the position of the pawl relative to the ratchet, to miss all of the ratchet teeth for maintaining the cam in its position of rest, to take all of the teeth for making the cam perform a cycle of operation, and to take the high teeth but miss the low tooth whereby the cam will come to rest at its starting point, said controlling means comprising a shield for the pawl with a connection for adjusting the shield automatically.
8. In a full fashioned knitting machine, a pair of adjustable stops on opposite sides of a transverse center line of the machine for arresting reinforcing yarn guide carriers for defining the reinforced area of the fabric, a pair of reciprocable members each carrying one of said stops, a pair of rotatable members having their axes at right angles to the direction of motion of the

reciprocable members, a reciprocable bar movable in a direction at right angles to both the direction of motion of the reciprocable members and to the axes of the rotatable members, a driving connection between said reciprocable bar and said rotatable members, and separate driving connections between the rotatable members and said reciprocable members.

9. In a full fashioned knitting machine a pair of adjustable stops on opposite sides of a transverse center line of the machine for arresting reinforcing yarn guide carriers for defining the reinforced area of the fabric, a pair of reciprocable members each carrying one of said stops and extending across said center line, a pair of rotatable members on opposite sides of said center line and having their axes at right angles to the direction of motion of the reciprocable members, separate driving connections between the rotatable members and the reciprocable members, the stop on one side of said center line being controlled by the rotatable member on the other side of said center line, and a common reciprocable bar for actuating said rotatable members.

KENNETH HOWIE. 25
